MOISTENING DEVICE FOR SOLE CUTTING MACHINES

Albert Roy and Armand Roy, Lawrence, Mass.

Application March 29, 1944, Serial No. 528,514

8 Claims. (Cl. 12—1)

1

This device is particularly for use with sole cutting machines such as shown in United States Letters Patent to P. J. McGowan, No. 1,645,441 of October 11, 1927, or it may be used with other machines of a similar type for a similar purpose.

It is found convenient in using such machines to have the work or stock to be cut fed in sheets perhaps eight feet long and twelve inches in width and it has been found that rubber or other similar stock must be moistened and must be moist or wet while the cutting knife travels, usually at an angle, around the form.

As now used, each such machine requires two operators. One operates the treadle which controls the valve in an air pressure line which admits air to and allows it to exhaust from a cylinder in which moves a piston carrying an auxiliary table on which part of the stock rests whereby part of the stock is moved up against the form, while another operator feeds the stock and also keeps wet the part of it which is about to be cut by using a sponge which he dips in a pail of water, squeezes and passes over the stock manually. These sponges are expensive, they wear out rapidly and the presence of a pail of water and a saturated sponge near the machine causes the floor to be wet and slippery.

This device includes a spray nozzle connected with a water container and preferably operated by compressed air from the air pressure supply which operates the piston in the cylinder which lifts the auxiliary work table.

The spray is controlled either by the single treadle which opens the air valve to that cylinder and shuts it off, allowing the air in the cylinder to escape to the spray device, or from another air control valve in the air supply from the same source of air pressure, controlled by another treadle or pedal which may be located next to the treadle for controlling the auxiliary table piston and cylinder.

The water may be from a tank which is intermittently or automatically kept supplied.

With either of these constructions, a single machine operator can take care of the moistening and can so regulate it that when the stock is moved up against the form, the spray is shut off and when the stock drops and just before or while it is advanced for the next cutting, the spray operates.

However, the spray might be controlled by a valve operated by means of a pedal, treadle or handle by another operator.

In the drawings,

Fig. 1 is a side elevation of our device and cer-

2

tain parts of the machine shown in patent to McGowan, Sole cutting machine, of October 11, 1927, No. 1,645,441.

Fig. 2 is a front elevation of the devices shown in Fig. 1.

Fig. 3 is a plan view of part of the main work table and the auxiliary table.

Fig. 4 is a detail of a preferred type of water spray nozzle.

Fig. 5 is a vertical sectional view of the valve in the bottom of the tank.

Fig. 6 is an elevation partly in section of the control valve for the piston and cylinder which operate the auxiliary table with our exhaust pipe connection.

Fig. 7 is a plan view, Fig. 8 is a front elevation and Fig. 9 is a side elevation of our preferred type of trough and tank.

Fig. 10 is a side elevation of a preferred form of air control pedal, valve and adjusting devices.

Fig. 11 is a sectional view through the treadle, pedal and operator's foot which engages both.

Fig. 12 is a longitudinal section through an air control valve such as shown in Fig. 10.

Fig. 13 is a side elevation of a tank or water container of a somewhat different type from the one shown in Figs. 1 to 9.

In the drawings, A represents the frame of a machine similar to the one shown in Patent No. 1,645,441.

K represents the work or sheet material to be operated on and L represents the work table as a whole. This work table L includes a main table 3 and an auxiliary table 74.

4 is a form detachably or otherwise secured, as indicated at 5, to a bracket arm 6 which is attached to an overhanging portion 1 of frame A and 9 is the knife adapted to be moved around the flange of a leader 33 closely adjacent to its periphery. This knife 9 is removably secured to an arm 10 and is operated by the same or similar machinery to that shown in the McGowan patent in his Figs. 6 and 7, and as described in his specifications on page 2, lines 23 to 73 and which it is not necessary to describe.

The auxiliary table 74 is secured to the head 77 of a piston 78 vertically reciprocable in a cylinder 79.

50 95 is a source of air pressure and the compressed air is conducted through an air pressure line G and an air control valve V having an inlet valve 100 in the main valve body 101 to cylinder 79. This inlet valve 100 is normally in position

55 to prevent any air from passing through valve

V into the part 117 of air pressure line G which connects with air cylinder 79.

This valve V is the same or substantially similar to the one shown in the McGowan patent and is operable by means of a T-shaped lever arm 109 pivoted at 110 and by a wire or rod 113 to a foot treadle 112. When this lever 109 is pulled down against the tension on the coiled spring 114, the air will pass from the air pressure line G through the valve body 101 and into the cylinder 79.

The result of this is that the piston 78 carrying the auxiliary table 74 is pushed up against the form 4.

When the pressure on treadle 112 is released, spring 114, pulls the T-lever 109 upwardly shutting off the air supply to cylinder 79 through port 116 and part 117 of line G and opening a passage 129 which is an exhaust port thus allowing the air to escape from cylinder 79 whereupon the auxiliary table 74 will drop to its normal position in line with the rest of the table 3.

The above devices are old and well known.

We utilize this compressed air escaping from the cylinder 79 through exhaust port 129 by connecting that port with an air nozzle 21 forming part of an atomizing or water spray device C by means of a connecting air pipe 25. Air flows through this pipe 25 and nozzle 21 until all that was trapped in cylinder 79 has been released.

The result of a knife such as 9 moving around a flange such as 33 is shown at 14, 14, in Fig. 3. The edges of the soles 14, 14, are usually beveled as the knife, arm and form are generally set for that purpose because a straight die action will not produce that result.

Our device includes a water container which, as shown in Figs. 1 to 9, may include a trough T in which is a tank B both carried independently by a stand F, as shown, or fastened in any suitable way to the work table L proximate the point where the work shown as sheet material K is about to be pushed along between the auxiliary table 74 and the form 4, and, in connection with the water container, a water spray device C which includes a water spray nozzle 20 and an air nozzle 21, adjoining the water spray nozzle. The air nozzle 21 of device C is connected to the main air pressure line G and is controlled by a valve therein.

As shown in Figs. 1 to 9, the trough T is rectangular and has the bottom 40 and side and end walls 41, 41, its top being open so that the tank B can be placed in it and removed therefrom.

Tank B is shown as of rectangular shape with the closed top 43, side and end walls 44, 44, and a bottom 45 through which is a valve hole 11 for a water control valve E. As shown the tank is carried by the legs 46, 46, and there is a port hole 49 in valve E through which passes stem 48 for plug 80, and other valve holes such as 82.

Projecting upward from the bottom 40 of trough T is a riser 47 adapted to engage the stem 48 of a common type of spring valve E. This valve E is located in hole 11 which it closes automatically by the movement of plug 80 carried by stem 48 and spring 81 when the stem 48 is not in contact with the riser 47.

The water level in the trough part of the container is therefore kept steadily at the level of the port 49 and when the tank B is to be refilled, the valve E can be unscrewed, the tank filled, the valve E replaced, and tank B turned upside down in trough T thus allowing the water

to run from the tank into the trough and maintain a steady level.

Other types of water containers with suitable valves as shown in Fig. 13 connected with a regular water supply might be used and we do not confine ourselves to this one type of water container.

As shown, this water container is supported by a stand F which rests on the floor but it might be clamped on the side of the frame A as shown in Fig. 13.

C is a water spray device which as shown is adjustably attached to the trough T by means of a bracket D so that its water spray nozzle 20 and air nozzle 21 can be directed up or down and to one side or the other onto the work K. As shown, air nozzle 21 carries spray nozzle 20 by means of an arm 22 and 23 represents a water spray pipe, for nozzle 20, which extends down into the trough T.

The bracket D to support the device C includes two arms 30, 31, at right angles with each other each having a slot 32 or 33. As shown, a bolt 34 is fixed to trough T and passes through slot 32 and by means of a winged nut 35 the arm 30 can be raised or lowered or swung sideways. Fixed to nozzle 21 is another screw or bolt 36 which passes through the slot 33 of the arm 31 and by means of a winged nut 37, the nozzles 20 and 21 of device C can be adjusted up or down or sideways.

There may be a drip lip which carries back any drops from the end of nozzle 20.

G represents the air pressure line from the source of air pressure 95 to the operating cylinder 79 and V represents the air control valve in that line with the exhaust port 129.

The air nozzle 21 by means of the air pipe 25 is connected with this exhaust 129 so that when the air is released from the cylinder 79 it escapes through the nozzle 21. This waste air from cylinder 79 therefore atomizes or causes a spray to be projected from the water nozzle 20 onto the work K when the knife is not cutting as the knife cuts only when piston 78 in cylinder 79 is held under pressure by the air from pressure line G, through air-control valve V.

Pressure on treadle 112 causes part of the work to be cut to be raised against form 4 and release 50 of pressure allows the next section which is to be cut to be advanced, raised and cut, to be sprayed and suitably moistened.

We find it convenient to utilize the well known T or McGowan type of air control valve such as V in the air pressure line G as it is only necessary to connect the air nozzle 21 of the water spray device C with its exhaust port 129 as by an air pipe 25.

However as shown in Figs. 10, 11, 12, the air for the spray device such as C can be controlled by a separate pedal such as P shown as pivoted at 61 with its foot arm 62 next to the arm of treadle 112, so that both pedals can be moved together by the operator's foot 100 as shown in Fig. 11, or each can be moved separately.

In this case, the exhaust air from a valve such as V through pipe 25 is not utilized and there is no pipe 25 as the air for the valve V is allowed to escape into the room when spring 114 causes T-shaped lever arm 109 to close inlet valve 101, and to open the exhaust port 129 in the usual manner in such machines and as shown by McGowan in his Figs. 4 and 5 and as he describes in his specification.

Instead of so doing, we can utilize the air pres-

5

sure from line G to and through a valve M, as shown in detail in Fig. 12. Valve M takes the place of the valve of the exhaust port 129, and part of pipe 50 takes the place of the pipe 25 from the exhaust port of the valve V, to the air spraying device C.

If the operator presses pedals 112 and P down together, the auxiliary table 74 is lifted and at the same time air through pipe 50, Fig. 13, to the air nozzle 21 of the water spray device C projects a spray or mist onto stock K while the cutting is going on. If more or less spray is desired, each pedal can be operated separately as follows.

Valve M is on the branch pipe 50 from main pipe G and is controlled by pedal P. Therefore as the treadle and pedal are both pushed down, while the cutting is being done, the spraying is being delivered on another part of the stock, and when the treadle 112 is released, if not enough spray has been delivered, the operator's foot can shift from both pedal and treadle, full lines Fig. 11, to the pedal P alone, dotted lines Fig. 11, and held as long as he wishes. Before he shifts his foot, a sole 14 has been cut and the spray is on another part of the stock K which he then moves with his hands on to table 74, and then presses 112 alone or with P, thus cutting another sole 14.

On the other hand, if he wishes to spray when not cutting, he can press down treadle 112 and hold it during the cutting and then, after it is released, he can shift to pedal P, spray as long as he wants to; then he can move the sprayed part over to table 74 to be cut; and then he can replace his foot on treadle 112 to cut another sole 14.

When the operator with his foot presses down part 62 of pedal P this lifts the other arm 60 with wheel 59 against a bend on an arm 58 of a rocker R pivoted at 55 with an operating arm 56 and a stop arm 57.

This operating arm 56 controls a well known type of air valve M in a pipe 50 which is tapped into the air pressure line G as shown at the top of Fig. 10 and has a port 51 normally closed by a plug 52 carried by a stem 53 and a spring 54.

64 is an adjusting screw which is threaded through arm 56 and rests on the end of stem 53 of valve M. It has a head 65 and a check nut 66 so that its exact relation with valve M can be regulated. When end 62 of pedal P is stepped on, it lifts the arm 60 and wheel 59 which engages the bent end of arm 58 and pushes that arm 58 to the right and moves arm 56 and pin 64 against the valve stem 53 with plug 52 thus opening the port 51 to allow air through pipe 50 to enter and flow through pipe 50 to air nozzle 21. 69 is a pedal returning spring.

As shown in Fig. 13, in place of the water container such as shown in Figs. 1 to 7, we can use a container N supported in any suitable way as by a bracket 73 on the frame A. 70 is a pipe line from water under pressure which ends in an inlet 71 which is opened or closed by a valve 72 controlled by a ball 74 in a well known manner so as to maintain the water level substantially the same. A bracket D carrying a water spray device such as C can be attached to container N in the same way as hereinbefore described.

On account of the different speed and peculiarities of different operators and of different stock, we find it desirable to provide for changing the quantity of water delivered to the water spray nozzle and the volume of air to the air nozzle.

When an additional pedal such as P and a

6

valve M are used, the air can be directed through nozzle 21 as long as desired and the regulation of the amount of water spray delivered is wholly under control, but the supply of air when T valve V is used is limited to the amount trapped in cylinder 79.

When the valve V is used, in order to change the amount of water spray to be delivered, we prefer to use an adjustable water valve such as shown in Fig. 4 at 26. This valve 26 is carried by the arm 22 and is provided with an under water inlet 27 in the tubular body 26.

Inside this tubular body 26 is a tubular stem 29 with an inlet port 28 opposite inlet 27, the stem 29 being also provided with a projecting lug or thumb piece 130 by turning which the amount of water which passes through the inlet ports 27 and 28 and therefore the amounts of water spray delivered can be increased or decreased or the water supply can be shut off entirely.

This is sometimes desirable so that the air blast from the nozzle 21 can be used for blowing dirt off from the work K.

Where a separate pedal such as P is used, we preferably provide adjusting screws such as 64 and 85 which engage a plate 84 so that the stem 53 of valve M can be moved more or less to allow more or less air to pass to the air spray nozzle such as 21.

However, we can use both the adjustment for the water nozzle and for the air nozzle or can omit either or both.

We claim:

1. The combination with a sole cutting machine having a frame, a work table carried thereby and including a main table and an auxiliary table normally flush with the main work table and carried by a vertically movable piston operable by air pressure in a cylinder whereby a part of the work on the main table can be lifted by air pressure from an air pressure line connected to the cylinder and to a source of air pressure; an air control valve with an operating arm interposed in the air pressure line to the cylinder from the source of air pressure, said valve being so arranged that when its operating arm is moved one way, air under pressure goes to the cylinder and when moved the other way it shuts off the air pressure and allows the cylinder air to escape through an exhaust port, a foot treadle and a connection to the operating arm of the valve to control the air going to and coming from the cylinder; of a water trough positioned near the main work table proximate the auxiliary table; a water tank positioned in the trough with a water level regulating valve in its bottom and positioned in the trough; and an air operable water spray device adjustably attached to the trough and including a water spray nozzle positioned proximate the auxiliary table, a water pipe from the water spray nozzle into the trough, an air nozzle adjoining the water spray nozzle; and an air connection from the air nozzle to the exhaust from the air valve.

2. The combination with a sole cutting machine having a frame, a work table carried thereby and including a main table and an auxiliary table normally flush with the main work table and carried by a vertically movable piston operable by air pressure in a cylinder whereby a part of the work on the main table can be lifted by air pressure from an air pressure line connected to the cylinder and to a source of air pressure; of a water trough positioned on the

main work table proximate the auxiliary table; a water tank positioned in the trough with a water level regulating valve in its bottom positioned in the trough; a water spray device attached to the trough and including a water spray nozzle pipe from the water in the trough to a water spray nozzle positioned near the side of the main work table proximate the auxiliary table, said water spray nozzle to direct a water spray on the auxiliary table, an air nozzle adjoining the water spray nozzle; an air connection from the air nozzle to the air pressure line; a valve in said air pressure line; and a foot pedal to control said valve.

3. The combination with a sole cutting machine having a frame, a work table carried thereby and including a main table and an auxiliary table normally flush with the main work table and carried by a vertically movable piston operable by air pressure in a cylinder whereby a part of the work on the main table can be lifted by air pressure from an air pressure line connected to the cylinder and to a source of air pressure; of a water container positioned near the main work table proximate the auxiliary work table; an air operable air spray device including a water spray nozzle positioned proximate the auxiliary work table, a pipe from said water spray nozzle to the water container and an air nozzle adjoining the water spray nozzle; an air connection from the air nozzle to the air pressure line; and valve means to control the passage of air through such air connection.

4. The combination with a sole cutting machine having a frame, a work table carried thereby and including a main table and an auxiliary table normally flush with the main work table and carried by a vertically movable piston operable by air pressure in a cylinder whereby a part of the work on the main table can be lifted by air pressure from an air pressure line connected to the cylinder and to a source of air pressure; an air control valve interposed in the air pressure line to the cylinder from the source of air pressure, said valve being so arranged that when its operating arm is moved one way, air under pressure goes to the cylinder and when moved the other way it shuts off the air pressure and allows the cylinder air to escape through an exhaust port, a foot treadle and a connection to the operating arm of the valve to control the air going to and coming from the cylinder; of an air operable water spray device including a water spray nozzle pipe from a source of water supply to a water spray nozzle positioned proximate the auxiliary table, said water spray nozzle and an air nozzle adjoining the water spray nozzle; an air connection from the air nozzle to the air pressure line; and valve means to control the passage of air through such air connection; together with a pedal positioned proximate said treadle to control the movements of said last named valve means.

5. The combination with a sole cutting machine having a frame, a work table carried thereby and including a main table and an auxiliary table, normally flush with the main work table and carried by a vertically movable piston operable by air pressure in a cylinder whereby a part of the work on the main table can be lifted by air pressure from an air pressure line connected to the cylinder and to a source of air

pressure; of an air operable water spray device including a water spray nozzle pipe from a source of water supply to a water spray nozzle positioned proximate the auxiliary table, said water spray nozzle and an air nozzle adjoining the water spray nozzle; an air connection from the air nozzle to the air pressure line; and valve means to control the passage of air through such air connection.

10 6. The combination with a sole cutting machine having a frame, a work table carried thereby and including a main table and an auxiliary table normally flush with the main work table and carried by a vertically movable piston operable by air pressure in a cylinder whereby a part of the work on the main table can be lifted by air pressure from an air pressure line connected to the cylinder and to a source of air pressure; of means operable by air from the air pressure line to spray liquid on the work as it rests on the work table.

15 7. The combination with a sole cutting machine having a frame, a work table carried thereby and including a main table and an auxiliary table normally flush with the main work table and carried by a vertically movable piston operable by air pressure in a cylinder whereby a part of the work on the main table can be lifted by air pressure from an air pressure line connected to the cylinder and to a source of air pressure; of means to spray liquid on the work as it rests on the work table; together with foot operable means to control the air pressure in the cylinder and to control the means to spray liquid on the work when it is on the work table.

20 8. The combination with a sole cutting machine having a frame, a work table carried thereby and including a main table and an auxiliary table normally flush with the main work table and carried by a vertically movable piston operable by air pressure in a cylinder whereby a part of the work on the main table can be lifted by air pressure from an air pressure line connected to the cylinder and to a source of air pressure; of means to spray liquid on the work as it rests on the work table; together with foot operable means to control the air pressure in the cylinder and to control the means to spray liquid on the work when it is on the work table.

25 9. The combination with a sole cutting machine having a frame, a work table carried thereby and including a main table and an auxiliary table normally flush with the main work table and carried by a vertically movable piston operable by air pressure in a cylinder whereby a part of the work on the main table can be lifted by air pressure from an air pressure line connected to the cylinder and to a source of air pressure; of means to spray liquid on the work as it rests on the work table; together with foot operable means to control the air pressure in the cylinder and to control the means to spray liquid on the work when it is on the work table.

30 10. The combination with a sole cutting machine having a frame, a work table carried thereby and including a main table and an auxiliary table normally flush with the main work table and carried by a vertically movable piston operable by air pressure in a cylinder whereby a part of the work on the main table can be lifted by air pressure from an air pressure line connected to the cylinder and to a source of air pressure; of means to spray liquid on the work as it rests on the work table; together with foot operable means to control the air pressure in the cylinder and to control the means to spray liquid on the work when it is on the work table.

35 11. The combination with a sole cutting machine having a frame, a work table carried thereby and including a main table and an auxiliary table normally flush with the main work table and carried by a vertically movable piston operable by air pressure in a cylinder whereby a part of the work on the main table can be lifted by air pressure from an air pressure line connected to the cylinder and to a source of air pressure; of means to spray liquid on the work as it rests on the work table; together with foot operable means to control the air pressure in the cylinder and to control the means to spray liquid on the work when it is on the work table.

40 12. The combination with a sole cutting machine having a frame, a work table carried thereby and including a main table and an auxiliary table normally flush with the main work table and carried by a vertically movable piston operable by air pressure in a cylinder whereby a part of the work on the main table can be lifted by air pressure from an air pressure line connected to the cylinder and to a source of air pressure; of means to spray liquid on the work as it rests on the work table; together with foot operable means to control the air pressure in the cylinder and to control the means to spray liquid on the work when it is on the work table.

45 13. The combination with a sole cutting machine having a frame, a work table carried thereby and including a main table and an auxiliary table normally flush with the main work table and carried by a vertically movable piston operable by air pressure in a cylinder whereby a part of the work on the main table can be lifted by air pressure from an air pressure line connected to the cylinder and to a source of air pressure; of means to spray liquid on the work as it rests on the work table; together with foot operable means to control the air pressure in the cylinder and to control the means to spray liquid on the work when it is on the work table.

50 14. The combination with a sole cutting machine having a frame, a work table carried thereby and including a main table and an auxiliary table normally flush with the main work table and carried by a vertically movable piston operable by air pressure in a cylinder whereby a part of the work on the main table can be lifted by air pressure from an air pressure line connected to the cylinder and to a source of air pressure; of means to spray liquid on the work as it rests on the work table; together with foot operable means to control the air pressure in the cylinder and to control the means to spray liquid on the work when it is on the work table.

55 15. The combination with a sole cutting machine having a frame, a work table carried thereby and including a main table and an auxiliary table normally flush with the main work table and carried by a vertically movable piston operable by air pressure in a cylinder whereby a part of the work on the main table can be lifted by air pressure from an air pressure line connected to the cylinder and to a source of air pressure; of means to spray liquid on the work as it rests on the work table; together with foot operable means to control the air pressure in the cylinder and to control the means to spray liquid on the work when it is on the work table.

60 16. The combination with a sole cutting machine having a frame, a work table carried thereby and including a main table and an auxiliary table normally flush with the main work table and carried by a vertically movable piston operable by air pressure in a cylinder whereby a part of the work on the main table can be lifted by air pressure from an air pressure line connected to the cylinder and to a source of air pressure; of means to spray liquid on the work as it rests on the work table; together with foot operable means to control the air pressure in the cylinder and to control the means to spray liquid on the work when it is on the work table.
